UNITED STATES PATENT OFFICE.

ARTHUR SAM CHESTON, OF BIRMINGHAM, ENGLAND.

BUFFER DEVICE FOR DOORS.

1,128,105.

Specification of Letters Patent.

Patented Feb. 9, 1915.

Application filed July 18, 1914. Serial No. 851,823.

To all whom it may concern:

Be it known that I, ARTHUR SAM CHESTON, subject of the King of Great Britain, residing at 24 Norman road, Northfield, Birmingham, England, have invented certain new and useful Improvements in Buffer Devices for Doors, of which the following is a specification.

This invention relates to a device adapted to be fitted to doors of motor-cars and other vehicles, or of buildings and the like, for the purpose of preventing rattling and for relieving the hinges of undue weight and obtaining correct positioning of the doors; said device preventing vertical movement and insuring the lock-bolts and moldings always being in perfect alinement.

According to the invention the device is adapted to be applied to the edge of the door, window, or the like, and comprises a circular buffer of rubber, felt, or similar material, rotatably mounted upon a suitable attachment plate and arranged to engage with a similarly shaped recess in the fixed frame. The buffer may, however, be upon the fixed frame instead of upon the door itself.

Figure 1 of the accompanying drawings shows the application of the invention to a motor-car door, the device being represented in section. This view shows the door partly open. Fig. 2 shows how the buffer (represented in plan) engages within the recess in the door pillar when the door is closed. Fig. 3 is a section on line α , Fig. 2, with the buffer partly in elevation. Fig. 4 illustrates a perspective view of the buffer as fitted to the edge of the door. Fig. 5 shows the recess in the standing door pillar to receive the buffer. Fig. 6 represents the attachment plate with the buffer (shown separately with its fixing screw) removed.

Secured within a recess in the rabbet of the said door 1 is an attachment plate 2 provided with a semi-circular wall or flange 3 which fits the sides of the said recess. This attachment plate 2, which is secured by screws 4, is provided with a circular boss or collar 5 surrounding a central internally screwed hole.

Rotatably mounted upon the plate 2, by means of a screw 6 taking into the screwed hole in said plate, is a circular buffer 7 made of rubber, felt, or similar material, and in the form of a roller. This buffer closely fits the semi-circular wall 3 of the plate 2,

and projects slightly beyond the end of the door as shown. Its outer end is recessed to receive the head of the screw, which has a washer 8 beneath its head, and the underside of the said buffer is also recessed to receive the boss or collar 5. If desired the hole through the buffer may be suitably bushed.

The rabbet of the fixed or standing door post 9 is formed with a semi-circular recess within which is fitted a curved wearing or shoe plate or liner 10 carried by a plate 11 secured by screws.

When the door is closed the buffer 7 engages with or rolls into the semi-circular shoe-plate 10 and holds the door in position, as the buffer is prevented from any vertical or lateral movements, thus preventing the door from rattling and also taking the weight off the hinges.

If desired the buffer roller may be carried by the fixed door post 9, and the edge of the door fitted with a sunken shoe or plate to receive the said buffer.

Preferably one of the silencing devices is fitted near the top of the door and another near the bottom.

It is found by this invention that much greater latitude can be allowed for the fall of doors than usual, and in the case of side-entrance and two-seater cars it will prevent the boxing on the standing pillars from becoming split.

Having fully described my invention, what I desire to claim and secure by Letters Patent is:—

1. The combination with a hinged door, and a fixed frame coöperative therewith, of a yielding roller mounted upon the edge of one part and rotatable on an axis substantially radial to the axis of the door hinges, the other part having a substantially semi-circular recess to receive one side of the periphery of said roller and thereby position the door.

2. The combination with a hinged door, and a fixed frame coöperating therewith, of a rotatable roller made of a yielding material pivotally mounted upon the edge of the one part on an axis radial to the door hinges, the other part having a substantially semi-circular recess in its edge with which the roller does engage, substantially as described.

3. The combination with a hinged door, and a fixed frame coöperating therewith, of a plate secured to the one part and having

a substantially semi-circular flange, a yielding roller rotatably mounted upon said plate on an axis radial to the door hinges and lying closely within said flange, and a 5 substantially semi-circular plate let into the other part adapted to be engaged by the roller, substantially as described.

4. The combination with a hinged door, and a door framing, an attachment plate let 10 into the rabbet in the edge of the door and having a substantially semi-circular peripheral flange at the inner side, a roller made of yielding material rotatably mounted upon

an axis radial to the door hinges and carried by the attachment plate and a substantially semi-circular wearing plate carried 15 by a side plate let into and secured within a recess in the rabbet of the door frame so as to be adapted to be engaged by the roller.

In testimony whereof I have hereunto set 20 my hand in presence of two subscribing witnesses.

ARTHUR SAM CHESTON.
